UNITED STATES PATENT OFFICE.

FRANCIS J. HOBSON AND CHARLES E. BEYER, OF NOGALES, ARIZONA.

ORE-SEPARATOR.

1,085,256.

Specification of Letters Patent.

Patented Jan. 27, 1914.

Application filed July 29, 1913. Serial No. 781,788.

To all whom it may concern:

Be it known that we, FRANCIS J. HOBSON, a citizen of the United States, and CHARLES E. BEYER, a subject of the King of Great Britain, both now residing at Nogales, in the county of Santa Cruz and State of Arizona, have invented certain new and useful Improvements in Ore-Separators, of which the following is a specification.

10 Our invention relates principally to that class of separating means utilized in metallurgical processes in which the materials to be separated are crushed with water or mill solutions, and where it is advisable or necessary to separate the coarser from the finer particles, or where it is advisable to make a number of classifications of finely divided material for subsequent metallurgical operations such as concentration, amalgamation, 15 lixiviation, cyanidization, etc., but it may be used for any purpose where separation or classification of finely divided material is advisable or necessary.

20 The object of our invention is to provide an improved construction of an efficient mechanical separator, which can be used, one by itself, or in series, where more than two classifications are necessary and in the several parts are compactly arranged and 25 which require a relatively small space and but a little loss in head from that ordinarily used for conveying gravimetrically finely divided material with water and solution.

With other objects in view that will hereinafter appear, our invention consists of a mechanical separator of the rotary type, that embodies the peculiar construction and novel arrangement of the parts hereinafter fully explained, specifically pointed out in 35 the appended claims and illustrated in the accompanying drawings, in which:—

Figure 1 is a plan view, parts being broken away of our improved rotary separator. Fig. 2 is a vertical longitudinal section thereof, taken on the line 2—2 on Fig. 1. Fig. 3 is a detail cross section of the same taken on the line 3—3 on Fig. 1. Fig. 4

is a detail perspective view of one end of the drum, the adjustable bearing at that end of the drum and the brake devices that co-operate therewith. Fig. 5 is a transverse section of our separator and showing an alternative method of driving the separator. Fig. 6 is a detail view of one of the vane holding disks hereinafter described, with 55 one vane attached. Fig. 7 is a detail perspective view of one of the said vanes. Fig. 8 is a detail perspective view of the shiftable divider and its supporting casing or flanges. Fig. 9, is a diagrammatic view 60 showing a plurality of separators in series.

In its practical arrangement, our rotary separator comprises a drum composed of end disks 1—1 and a series of transversely disposed vanes 2—2, all of like construction. 65 The several vanes, in the preferred construction are of flexible sheet iron and may be curved or straight, they being shown curved. Each end disk has a series of grooves 3 on the inner face which are curved 70 to the cross sectional shape of the blades or vanes, and these in fitting up the parts are slid edgewise into the said grooves. The drum also includes a plain cast hollow cylinder 4, the ends 5 of which have apertures or 75 bearings 6 for a central shaft 7 and the said cylinder ends 5 are fixedly attached to the shaft 7 to rotate therewith. To the cylinder ends 5 are screwed the end disks 1 that carry the vanes 2, as clearly shown in Fig. 80 3 of the drawing.

8 designates a trough or cast iron box that is open at the top at one end, and at the bottom, it having inside flanges 9 at the bottom (see Figs. 5 and 8) the purpose 85 of which will presently appear. For co-operating with the drum and to provide, as it were, a casing in which the upper end of the drum rotates, we provide an iron cover 10 formed at the top with a rectangular hopper or feed box 11. Cover 10 is fitted to the upper horizontal flanges 12 of the trough 8, it having lugs 13, that receive the clamp bolts 14 that pass through elongated

slots 15 in the said flanges 12, to permit of moving the cover forwardly or backwardly on the trough for the desired adjustment of the discharge of the machine.

5 16—16 designate the bearings for the central shaft 7 and they are adjustably secured on the trough flanges 12 by the bolts 18 that pass through the slots 17 in the said flange 12.

10 The entire apparatus can be supported on timbers 19 bolted to flanges 20—20 on the trough 8, as shown in Fig. 1, or in any other suitable and convenient manner.

15 21 designates what we term the divider, and the same consists of a bottom member in the nature of a plain angular casting which rests of its own weight on the inside flanges 9 of the trough (see Fig. 8). The divider, by reason of its being loosely supported so it may be moved forward or backward, can be readily set to adjust the discharge of the machine.

20 In the preferred construction shown, the drum is arranged for being driven by power generated by the material and water that passes through the separating machine. In practice, we have found that more than sufficient power is so generated that it is necessary to use a brake or retarding means. We 25 have shown a brake composed of a friction block 22, having a concaved seat 23 for engaging the flanged collar 24 keyed on the extended end of the shaft 7. Block 22 is controlled by a lever 25 pivotally mounted 30 on a bracket 26 adjustably connected to the trough flange 12; said lever seats in a groove 27 on the top of the block 22 and is held down by the adjustable weight 28, all clearly 35 shown in Fig. 4 of the drawings. In Fig. 5 we have shown a pulley 29 on the shaft 7, which may be driven by a belt, worm gear or any other practical power transmission 40 means.

45 In operation, the crushed or finely divided material with water or solution is delivered into the hopper 11 from where it drops into the several pockets or spaces formed between the vanes 2, which in practice are caused to revolve in the direction indicated by the 50 arrow 30 in Fig. 2. When operating for the separation of ore, sands and slimes, the slimes are held in suspension in the water or solution, until the vanes arriving at a position low enough in the path of rotation, at 55 which time, most of the solution is discharged or flows off onto the forward side of the divider 21, and with it the slimes, which are in suspension. After passing the apex of the divider the heavier particles, the 60 sands, and the remainder of the water or solution, gravitate to the other side of the sand divider 21. At this point it should be mentioned that at the inner or back and each

vane has small apertures 32 for the admission of air for overcoming a suction forming which would have a tendency to carry the sands over the inner cylinder. The amount of slimes or fine material separated is adjusted by the setting of the divider 21, changing the position of the drum and its 65 cover in relation to the trough and the divider 21, and by adjusting the speed with which the drum revolves.

70 As before stated, when more than two classes of material are necessary or advisable, two (or more) machines can be run in series, (see for example Fig. 9) and the desired number of separations be thereby made, the feed for the second or series separators being taken from either discharge of 75 the preceding separator, governed by the 80 character of the material used.

85 From the foregoing taken in connection with the drawings, the complete construction, the operation and the advantages of our invention will be readily apparent to those skilled in the art to which our invention relates.

What we claim is:

1. A rotary separator composed of end 90 disks, a hub and a series of transverse vanes that divide the drum into a series of radial pockets, the vanes having apertures for the circulation of air in the hub ends of the pockets, and means for dividing the material 95 discharged from the separator.

2. A rotary separator composed of end disks, a hub and a series of transverse vanes that divide the drum into a series of radial pockets, the vanes having apertures for the 100 circulation of air in the hub ends of the pockets, and an adjustable means for dividing the material discharged from the separator.

3. In a rotary separator, a trough, a drum 105 journaled to rotate within the trough, a cover mounted on the trough over the drum and having a feed inlet at a point above the drum, the latter including a hub, and a series of pockets that radiate from the hub, 110 and an adjustable means for dividing the material discharged from the drum, said cover being mounted in close proximity to said drum and conforming to the curvature 115 of the same to form a substantial closure for the peripheries of the pockets of the drum.

4. A self-propelling rotary separator comprising an open bottom hopper, a drum journaled to rotate in the hopper, said drum including a driven shaft, a hollow cylinder 120 mounted on and to rotate with the shaft, end disks secured to the cylinder and a series of transverse blades that divide the drum into radial pockets, and a cover mounted on the hopper over the upper half of the drum and 125 in close proximity to the pockets to form a

closure therefor, said drum having an opening at the top, and a feed box mounted on said cover to discharge through said opening.

5. A rotary separator composed of end disks, a hub and a series of transverse vanes that divide the hub into a series of radial pockets, the said vanes being perforated for overcoming suction at their point of discharge.

10 6. A rotary separator composed of end disks, a hub, a series of transverse vanes that extend from the hub outwardly to form a series of radial pockets, said vanes being of

concave form, and being perforated for overcoming suction that occurs at the point of discharge of the vanes.
